UNITED STATES PATENT OFFICE.

MAURICE W. STAVRUM, OF CHICAGO, ILLINOIS.

DESIGN FOR A LOOP ANTENNA.

Application filed January 4, 1927. Serial No. 20,280. Term of patent 7 years.

To all whom it may concern:

Be it known that I, MAURICE W. STAVRUM, a citizen of the United States, residing at 4884 North Clark Street, Chicago, in the county of Cook and State of Illinois, have invented a new, original, and ornamental Design for Loop Antenna, of which the following is a specification, reference being had to the accompanying drawing, forming part thereof.

In the drawing—

Fig. 1 is a side elevation of my new design for loop antenna; and

Fig. 2 is a top plan view of the same.

I claim:

The ornamental design for a loop antenna as illustrated.

MAURICE W. STAVRUM.
